Attorney.

UNITED STATES PATENT OFFICE.

RUDOLF HASE, OF HANNOVER, GERMANY, ASSIGNOR TO THE FIRM NAAMLOOZE VEN-
NOOTSCHAP FINANZIELE MAATSCHAPPIJ "DRIEBERGEN," OF AMSTERDAM,
NETHERLANDS, A COMPANY OF THE NETHERLANDS.

TELEPHONOGRAPH AND LIKE INSTRUMENT.

Application filed July 30, 1921. Serial No. 486,731.

To all whom it may concern:

Be it known that I, RUDOLF HASE, a citizen of the German Republic, engineer, residing at Josephstrasse 26, Hannover, Germany, have invented new and useful Improvements in Telephonographs and like Instruments, of which the following is a specification.

This invention relates to telephonographs and like instruments wherein two cylinders are employed, the one being automatically brought into action upon the completion of the record upon the other.

The chief purpose of the invention is to improve the junction between the records upon the two cylinders. To this end the invention makes provision for each cylinder to be automatically brought up to speed before the other is put out of action. In a preferred construction the records are made actually to overlap a little, for which purpose the one cylinder is put into action before the other is switched off.

In a preferred embodiment of the invention the moving slide carrying the sound box of the instrument is caused to operate a plurality of electrical contacts in succession at a predetermined time interval. By its first contact operation the moving part sets in motion the cylinder theretofore stationary; and by a subsequent contact operation it interrupts the drive of the cylinder which was first in rotation.

The invention further includes a system of connections including a relay and contacts operated thereby which govern both the circuit of an electric driving motor and also the circuit of the sound box of the apparatus.

By way of example a construction according to the invention is illustrated diagrammatically in plan in Fig. 1 and its electrical connections are shown in Fig. 2.

In this embodiment of the invention the apparatus consists of two completely similar parts. Each includes a cylinder A, A' with an inscribing sound box B, B' and a reproducing sound box which is not shown. Both boxes of each portion of the apparatus are carried by a slide C, C' which is

traversed upon rods D, D' parallel to the axis of its cylinder by a driving motor, also not shown. Upon each part of the apparatus are press buttons E, F and E', F' respectively, controlling circuits as hereinafter explained with reference to Fig. 2; and for each part of the apparatus there is also provided a hand operated switch G, G'. Depression of the press button E or E' closes the respective circuit, and depression of the press button F or F' opens the circuit. Each of the switches G and G' is included in the circuit of an electromotor driving that part of the apparatus to which the switch belongs, and the switches are of such construction as to return automatically to open circuit position after they have been closed and released.

Upon each of the slides C, C' on that side of it which travels foremost in the operative traverse of the slide are arranged two pins H, J, H', J' respectively. These are adapted to operate one after the other upon two contacts in end blocks K, K'. As indicated, the pins H, J are made of different length for this purpose.

The method of operation may be explained by reference to the diagram of Fig. 2. In this diagram 1, 1' indicate the contacts which are closed by depression of the press buttons E, E' respectively and which are opened by depression of press buttons F, F' respectively. The contacts of the switches G and G' are shown at 2 and 2' respectively. The driving motors for the cylinders A and A' are indicated in the diagram at L and L' respectively. M, M' are relays appropriated to the respective halves of the apparatus and each of them has two contacts 5, 6, 5', 6', which are closed when the relay is excited. The contacts operated by the pins in the slide C, C' are shown at 3 and 4 and 3' and 4' respectively. During the travel of the sound box, 3 or 3' is closed while 4 or 4' is opened.

When the telephonograph is to be put into action both press buttons E, E' are depressed so as to close contacts 1 and 1'. Also one of the two switches G, G' is closed, so as to close, say, contact 2. Consequently

- current flows over the circuit, positive pole 7 of the mains, relay M, switch 2, motor L, contact 1, contact 3, to the negative pole 8 of the mains. Motor L starts up and relay 5 M is excited and closes its contacts 5 and 6. Contact 5 is in parallel with contact 2 and therefore maintains the circuit of the motor L closed when the switch G is released and returns to its open circuit position. The 10 closing of contact 6 completes the circuit of the sound box B shown in dotted lines, said circuit ending at terminals 9, 10 which may be supposed connected, for instance, to a thermionic valve or other amplifying device. 15 The sound box B, therefore, begins to inscribe the conversation in cylinder A. Upon the sound box slide C nearing the end of its traverse, its pin H first closes the contact 4 so as to establish a circuit as follows: 7, 20 M', 4, L', 1', 3', 8. The motor L' therefore starts up and relay M' closes its two contacts 5', 6', the latter of which completes the circuit of sound box B'.

For a certain length of time, therefore, 25 both parts of the apparatus are in action together and the conversation is recorded in, or reproduced from, both record carriers A and A'.

At the end of the traverse, however, the 30 pin J of the slide C opens contact 3 which breaks the circuit of motor L and relay M. The contacts 5, 6 of the latter therefore open, so breaking the circuit of sound box B. The second half of the apparatus is then 35 alone in operation.

The cylinder A can now be removed and replaced by another and slide C can be returned to its initial position. Such movement of it closes contact 3 and opens contact 4. Initially the circuit of relay M' and motor L' was completed over contact 4; but upon excitation of relay M' its contact 5', which is in parallel with contact 4, was closed and the motor- and exciting-circuit therefore remains completed over this 45 contact.

It will be clear from this description and the diagram of connections that it is immaterial which of the two parts of the apparatus is first put in action.

The invention is not restricted to the details of construction described and illustrated since these may be varied without affecting the substance of the invention.

55 What I claim is:

1. In a sound recording and reproducing instrument, the combination of two record carriers, a member traversing one of said record carriers, means for driving each of 60 said carriers and said member, means operated by said member near the end of its traverse for setting the other carrier in motion, and means operated by said member on reaching the end of its traverse for 65 stopping the carrier it has traversed.

2. In a telephonograph the combination of two cylinders, a sound box co-acting with each cylinder, means for rotating each cylinder and traversing its sound box along it, means automatically actuated by each sound 70 box before reaching the end of its traverse for starting the other cylinder and its sound box, and means automatically actuated by each sound box on reaching the end of its traverse for stopping its cylinder and putting itself out of action. 75

3. In a telephonograph, the combination of two cylinders, a sound box for each cylinder, an electric motor for each cylinder and connections between said motor and its 80 cylinder and sound box whereby the cylinder may be rotated and the sound box traversed over it, a source of power, a contact closed by the sound box of one cylinder near the end of its traverse completing a circuit 85 for the motor of the other cylinder from said source of power, and a contact opened by said sound box on reaching the end of its traverse breaking the circuit of the motor driving it. 90

4. In a telephonograph, the combination of two cylinders, a sound box for each cylinder, an electric motor for each cylinder and connections between said motor and its cylinder and sound box whereby the cylinder may be rotated and the sound box traversed over it, a source of power, two contacts in the circuit of each motor completing its connection to said source of power, one of said contacts lying in the path of 100 the sound box driven by said motor and adapted to be opened thereby at the end of its traverse, and the other lying in the path of the other sound box and adapted to be closed thereby before it reaches the end of 105 its traverse.

5. In a sound recording and reproducing instrument, the combination of two record carriers, a sound box for each record carrier co-operating therewith, a motor for each carrier driving said carrier and traversing its sound box over it, a source of power, a relay for each motor, a hand-operated switch for each motor, connections between each said switch, its motor and relay and the source of power forming a closed circuit upon the closing of said switch, a contact in parallel with each switch closed by the associated relay upon its excitation, and a second contact in parallel with each switch 115 closed by the operation of the motor not associated with that switch prior to the completion of the traverse of the sound box driven by that motor. 120

6. A telephonograph comprising two 125 parts, each part including a cylinder, a sound box, an electric motor driving said cylinder and traversing said sound box along it, a relay, a hand-operated switch, and connections between said switch, motor 130

and relay whereby the closing of the switch completes a circuit through said motor and relay, a contact in parallel with said switch closed by said relay upon its excitation, a second contact in parallel with said switch closed by the sound box of the other part of the telephonograph near the end of its traverse, and another contact operated by said relay and controlling the circuit of the sound box. ¹⁰ In testimony whereof I have signed my name to this specification.

RUDOLF HASE.
